US0D1061757S

(12) **United States Design Patent** (10) Patent No.: **US D1,061,757 S**
(45) Date of Patent: ** Feb. 11, 2025

(54) **BARBELL**

(71) Applicants: **Tyler Phillips**, Germantown, MD (US);
William Stefany, Gaithersburg, MD (US)

(72) Inventors: **Tyler Phillips**, Germantown, MD (US);
William Stefany, Gaithersburg, MD (US)

(73) Assignee: **RentACoop, LLC**, Germantown, MD (US)

(**) Term: **15 Years**

(21) Appl. No.: **29/861,453**

(22) Filed: **Nov. 30, 2022**

(51) LOC (15) Cl. **21-02**

(52) U.S. Cl.

USPC **D21/681**

(58) **Field of Classification Search**
